CLAIM

The ornamental design for a hair color analyzer with cradle, as shown and described.

DESCRIPTION

FIG. 1 is an exploded perspective view showing our new design;

FIG. 2 is a front elevational view of the assembled design;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof;

FIG. 8 is a front elevational view of said hair color analyzer;

FIG. 9 is a rear elevational view of the analyzer portion of our design, shown separate from the assembly for clarity and completeness of disclosure;

FIG. 10 is a top view thereof;

FIG. 11 is a right side elevational view thereof;

FIG. 12 is a left side elevational view thereof;

FIG. 13 is a bottom view thereof;

FIG. 14 is a front elevational view of the cradle portion of our design, shown separate from the assembly for clarity and completeness of disclosure;

FIG. 15 is a rear elevational view thereof;

FIG. 16 is a right side elevational view thereof;

FIG. 17 is a left side elevational view thereof;

FIG. 18 is a top view thereof; and,

FIG. 19 is a bottom view thereof.
